UNITED STATES PATENT OFFICE.

LEWIS WEDSEL ABBOTT, OF WORTHINGTON, MINNESOTA, ASSIGNOR OF ONE-HALF TO ADOLPH AMONDSON, OF WORTHINGTON, MINNESOTA.

HEATING AND VENTILATING SYSTEM.

No. 849,346.

Specification of Letters Patent.

Patented April 2, 1907.

Application filed April 23, 1906. Serial No. 313,239.

To all whom it may concern:

Be it known that I, LEWIS WEDSEL ABBOTT, of Worthington, county of Nobles, State of Minnesota, have made certain new and useful Improvements in Heating and Ventilating Systems, of which the following is a specification.

This invention relates to improvements in heating and ventilating systems; and the objects I have in view are to provide a simple and inexpensive device that can be applied in connection with an ordinary heating-stove for taking a large amount of fresh air from the outside of the building and properly heating the same and distributing it to the room or apartment to be heated, and which will also take a part of the cold air from the lower part of the room and conduct it to the smoke-stack or chimney.

In the accompanying drawings, forming part of this specification, Figure 1 is a section of a portion of a room, showing my heating and ventilating system arranged therein. Fig. 2 is a horizontal section on line 2 2 of Fig. 1. Fig. 3 is a vertical section on line 3 3 of Fig. 1.

In the drawings, 2 represents a stove or heater of ordinary construction. This heater is provided with the usual fuel-door 3, with a heating-drum 4, and with a smoke-pipe 5, leading to the chimney 6. The opening into the chimney is preferably located near the ceiling 7 of the room to be heated. Surrounding the stove 2 is a sheet-metal drum 8, preferably open both at top and bottom and supported at a suitable distance above the floor 9 by the legs 10. This drum is provided with a suitable door 11, through which fuel may be supplied to the opening covered by the door 3 of the stove. Arranged within this drum and nearly surrounding the lower part of the stove is the conveyer 12, of nearly circular form and provided upon its inner wall with a series of openings 13. A pipe 14 leads from outside of the building and connects with the conductor 12. By this means a supply of fresh air from the outside atmosphere is brought in through the pipe 14 and carried in the conductor 12 substantially around the stove, and it escapes through all of the openings 13 and passes upward between the interior of the drum 8 and the exterior of the stove and enters the room. By

this means a large supply of fresh warm air is provided.

For the purpose of simultaneously taking away a portion of the cold foul air that collects near the floor of the room I provide a drum 15, surrounding the smoke-pipe 5 near the point where it enters the chimney. The pipe 16, of larger diameter than the pipe 5, connects the drum with the chimney, and in this pipe I provide a series of supports 17 for holding the pipe centrally within the pipe 16. A pipe 18, having an open lower end supported, preferably, upon suitable legs 19, extends from a point near the surface of the drum and connects with the drum 15. By this means the cold foul air is taken up from a point within a few inches of the floor of the room and is carried upward through the pipe 18, the drum 15, and the pipe 16 into the chimney. By placing the drum 15 near the ceiling, where the air is warm, and having the smoke-pipe from the stove pass through it the air in this drum will be heated and a strong draft through the pipe 18 will be created. The drum 8, surrounding the stove, prevents overheating persons or objects near the stove and directs fresh air brought in from outside the building through the pipe 14 upward along the surface of the stove, thereby causing said air to be heated to the proper temperature before escaping into the room or apartment to be heated.

It will be noted that with this system a large supply of fresh air is brought into the room from the outside atmosphere, that this air is evenly distributed around the stove or heater by the conveyer 12, and that it is then thoroughly heated as it passes upward between said conveyer and the outer surface of the stove or heater and between the inner wall of the drum above said conveyer and the outer surface of the stove, and that when it enters the room or apartment to be heated it is at a high temperature and in this condition is distributed through the room.

It will also be noted that the cold foul air lying along the floor of the room is drawn through the pipe 18 and conducted directly into the chimney. By this means I secure an efficient and economical heating system that can be inexpensively applied to any room or apartment that is to be heated.

The disadvantages arising from the heat-

ing of a room by direct radiation from a stove or heater are done away with, the drum surrounding the stove prevents overheating in the vicinity of the stove by direct radiation from its surface, and the arrangement for bringing the fresh air into the drum and around the stove provides an adequate ventilation and a proper tempering of the air that is thus brought into the room.

10 This system is especially adapted for school-rooms that are heated by means of stoves or separate heaters for each room, where a large number of children are kept for a considerable period of time in a single room. Usually such rooms are heated directly by stoves and no means for ventilation is provided. The air in such instances becomes foul, and the health of the children is seriously affected. By my system the rooms are adequately heated and fully ventilated.

15 The system is also equally advantageous for churches or other auditoriums.

The system is also applicable for the heating of private residences or other buildings.

20 The constant circulation of air within the room caused by the arrangement of the heating-drum and foul-air flue equalizes the temperature of the air in all parts of the room. The layer or stratum of hot air invariably found in the upper portion of all unventilated rooms is thus broken up and caused to mix with the other air of the room, and this, together with the fact that the cold or foul air flue is constantly drawing the cold and impure air from near the floor and discharging

it through the chimney-flue, renders it possible to properly heat a given room with much less fuel than it takes to heat the same room by the old process of direct radiation without ventilation.

25 I have shown the fresh-air pipe 14 provided with a suitable valve or damper 14' and the foul-air pipe 18 provided with a similar valve or damper 18'.

I claim as my invention—

30 1. The combination, with a heater, of a surrounding drum open at top and bottom, a conductor arranged within said drum and extending around said heater and provided with a series of openings upon its inner surface and a pipe leading from the outside atmosphere and connected with said conductor, substantially as described.

35 2. The combination, with a heater, of the drum 8 surrounding said heater and open at top and bottom, the conductor 12 arranged upon the inner wall of said drum and extending horizontally around said heater, provided with a series of openings 13 upon its inner surface and the pipe 14 connected with said drum and adapted to conduct air from the outside atmosphere into said conductor 12, substantially as described.

40 In witness whereof I have hereunto set my hand this 13th day of April, 1906.

LEWIS WEDSEL ABBOTT.
